UNITED STATES PATENT OFFICE

122,047

DESIGN FOR A DISPLAY STAND FOR AUTOMOBILE HORNS

Max Watson, Omaha, Nebr., assignor to Jubilee
Manufacturing Company, Omaha, Nebr., a cor-
poration of Nebraska

Application February 5, 1940, Serial No. 90,038

Term of patent 7 years

To all whom it may concern:

Be it known that I, Max Watson, a citizen of the United States, residing at Omaha, in the county of Douglas and State of Nebraska, have invented a new, original, and ornamental Design for a Display Stand for Automobile Horns, of which the following is a specification, reference being had to the accompanying drawing, forming part thereof.

Figure 1 is a perspective view of a display stand for automobile horns showing my new design.

Figure 2 is a top plan view thereof.

I claim:

The ornamental design for a display stand for automobile horns, as shown.

MAX WATSON.
